UNITED STATES PATENT OFFICE

MILTON HARRISON PAGE, OF COHOES, NEW YORK

SOUND RECORDING DEVICE

Application filed November 19, 1929. Serial No. 408,393.

The present invention relates to a device for recording sound waves, and more particularly to improved means for varying the amplitude or area of a beam of light in response to variations in a vibratory member and recording the modulated light on a sensitized film, strip or the like.

An essential object of the invention is to provide a vibrating member for cutting off a beam of light projected on a movable photo-sensitive film, said vibrating member being operable by the sound to be recorded and arranged to form on the film transverse images or undulations that represent the characters of the sound to be recorded.

A further object consists in a new and improved method of recording sound waves on a sensitized film or the like.

A further object consists in providing a substantially tapered or wedge-shaped vibrating member of less width than the projecting beam of light, so as to produce marginal dark bands adjacent the edges of the sound track portion of the film and coextensive with the length thereof, which bands prevent overshooting of the recording lines and act as a base for the sound track portion of the film.

Another object is to provide means for producing sound waves on a film, which waves are sharply defined so that the produced sounds will be clear and distinct; the recorded lines being formed in such a manner as to add amplitude to the recording and materially eliminate ground noises.

A still further object is to provide a sound recorded film with marginal base bands or lines and transverse images or undulating recorded bands that extend inwardly from both sides of the track portion of the film and form an intermediate blank area, the width of the recording images in their direction of movement representing the characteristics of the sound recorded and the length of the images indicating the amplitude or area of the vibrations.

Other objects of the invention will become apparent from the following description when taken in conjunction with the accompanying claims and drawing.

Referring to the drawing in which is shown a preferred embodiment of the invention:

Figure 1 is a side view of a recorder showing my invention applied thereto.

Figure 2 is a sectional view substantially 55 along the line 2—2 of Figure 1.

Figure 3 is an enlarged detail view of the vibrating member and its associated parts.

Figure 4 is a side elevation of a modified form of the invention with parts in section. 60

Referring to the drawing in which like numerals indicate like parts in the several views, 10 denotes an optical system arranged to project a beam of light 11 onto the track portion 12 of a sensitized film 13 for the purpose 65 of recording sound thereon.

A member 14 which is operatively associated with a suitable device, not shown, for collecting the sound to be produced, has connected thereto as at 15 a substantially L-shaped arm 16, the vertical portion of which terminates in a vibrating shutter 17 arranged to be moved into the path of the beam of light 11 by the member 14.

Obviously, the shutter 17 and its connection to the member 14 may assume various other forms so as to be projected into the path of a beam of light to record on a sensitized film, the modulated light when the vibrating member is brought into operation.

The film 13 is led from a guide roller 18 around a drum 19 in such a manner as to bring the sound track portion 12 into focal alignment with the projected beam of light 11 from the optical system 10. The film passes from the lower portion of the drum 19 around a guide roller 20 and is carried over to a roller 21 from where it may be conducted to any suitable point for winding.

The film 13 as it is advanced toward the optical system 10 has the track portion 12 thereof blank and as it passes the beam of light 11, the member 14 is actuated to cause the shutter 17 to be moved in accordance with the vibrations set up by the sound to be recorded, and transfer the images formed by the modulated light onto the sound track portion 12.

In order to accurately and clearly record the natural characteristics of the sound vibra-

tions and to eliminate or reduce ground noises, the vibrating shutter 17 is preferably substantially tapered or wedge-shaped (Fig. 3) and of less width than the beam of light in the path of which it is arranged to be projected, so that during the operation of the recorder, the shutter 17 when in its lowermost position will not completely cut off the light, but will allow portions thereof to be projected on the film so as to produce the dark bands 22 and 23 of constant or uniform width (Fig. 3) along the outer edges of the track portion 12, which bands extend lengthwise of the film and act as a base for preventing the transverse vibrations of light recorded on the sound track portion from extending beyond the edges thereof.

It will be seen that in the operation of the device the vibrating shutter 17 causes the record to be produced on the sound track portion in the form of transverse undulations or stirrations 24 and 25, which extend in staggered relation from the sides of the sound track portion. The width of the recorded images or vibrations 24 and 25 in their direction of movement designating the characteristics of the sound, while the length of the images represent the amplitude of vibration.

30 The adjacent sides of the images 24 and 25 are spaced from each other by a medial blank portion 26 which varies in width in accordance with the vibrations imparted to the shutter 17.

35 As shown in Figure 3, the lower portion of the film indicates how the dark bands 22 and 23 are formed when the shutter 17 is maintained in its lowermost position relative to the optical system 10.

40 In the modified form of the invention illustrated in Figure 4, means are provided for interrupting the light within the optical system and then projecting the modulated light onto the track portion of the film in the manner as previously described. In this form of the invention, the optical system 27 has mounted therein a partition member 28 having an aperture or slit 29 through which the concentrated beam of light passes and is interrupted by the vibrating shutter 30 connected to the member 31 as at 32. The shutter 30 is of less width than the opening 29 so as to form the bands 22 and 23 along the marginal sides of the track portion of the film while the member 31 is suitably connected to the sound to be recorded so as to cause the actuation of the shutter 30 in response thereto.

It is to be understood that the form of the invention shown and described is merely illustrative of preferred embodiments and that such changes may be made as fall within the purview of one skilled in the art without departing from the spirit of the invention and the scope of the appended claims.

I claim:

1. The method of recording sound waves on the track portion of a sensitized film, which consists in projecting a beam of light onto the film and modulating the amplitude of an intermediate portion of the light longitudinally of the sound track before it strikes the film in accordance with the variations in the sound waves so as to produce adjacent the sides of the sound track dark lines of uniform width that extend lengthwise of the film, and transverse undulations extending inwardly from said lines, each of said lines acting as a base for preventing the transverse undulations from extending beyond the edges thereof. 70 75 80

2. A sound recording device comprising an optical system, a sensitized film associated with said system for receiving a beam of light therefrom, a vibrating member operable by the sound waves to be recorded and having a substantially wedge-shaped shutter arranged to be moved into the path of light lengthwise of the sound track portion of the film to modulate the light before it reaches the film, said shutter being of less width than the beam of light so as to form definitely defined bands of uniform width adjacent the opposite sides of the sound track portion of the film, and transverse images extending inwardly from said bands, each of said bands acting as a base for preventing the transverse images from extending beyond the edges thereof. 85 90 95

3. A sound recording device comprising an optical system, a sensitized film, means for moving the sound track portion of the film past said optical system, a vibrating member operable by the sound waves to be recorded, and having a shutter provided with downwardly extending converging sides and arranged to be moved into the path of light before it strikes the film to modulate the light, said shutter being of less width than the beam of light so as to provide spaced bands of uniform width which extend lengthwise of the film adjacent the outer sides of the sound track portion, and transverse images extending inwardly from said bands, each of said bands acting as a base for preventing the transverse images from extending beyond the edges thereof. 100 105 110 115

4. A sound recording device comprising an optical system, a sensitized film, means for moving the sound track portion of the film past said optical system, a vibrating member operable by the sound waves to be recorded, and having a shutter arranged to be moved into the path of light before it strikes the film so as to modulate the same, said shutter being of substantially wedge-shape and of less width than the beam of light so as to produce adjacent the sides of the sound track dark bands of uniform width that extend 120 125 130

lengthwise of the film, and transverse undulations extending inwardly from said bands, each of said bands acting as a base for preventing the transverse undulations from extending beyond the edges thereof.

5 In testimony whereof I have hereunto set my hand.

MILTON HARRISON PAGE.
